United States Patent Office

Des. 188,391

Patented July 12, 1960

188,391

COMBINED CONTROL KNOB AND ESCUTCHEON

Monte Levin, Roslyn Heights, N.Y., assignor to International Associates, Rockville Centre, N.Y., a partnership

Filed Nov. 13, 1959, Ser. No. 58,337

Term of patent 14 years

(Cl. D50—3)

FIG. 1

FIG. 2

FIG. 3

Fig. 1 is a plan view of a combined control knob and escutcheon, showing my new design;

Fig. 2 is an edge view thereof; and

Fig. 3 is an edge view thereof at right angles to that shown in Fig. 2.

I claim:

The ornamental design for a combined control knob and escutcheon, substantially as shown.
